[57] ABSTRACT

A column-mounted shoring bracket adapted for use in first supporting a concrete slab-supporting formwork beam during concrete-pouring operations, then stripping the formwork from the hardened slab and lowering the thus released formwork, and finally permitting lateral withdrawal of the formwork from beneath the completed slab for purposes of reuse at a higher building level. A roller support for the beam is carried on a vertically slidable carriage which transfers the load of the beam to the lower end of a jack screw which is thus placed under tension. Rotation of the jack screw for carriage-lowering purposes places the jack screw under further tension and effects an initial stripping of the formwork from the slab immediately prior to lowering of the formwork.

SHEET 2 OF 2

**COLUMN-MOUNTED SHORING BRACKET
ASSEMBLY FOR OVERHEAD FORMWORK**

The present invention relates to a column-mounted shoring bracket for supporting pallet-type concrete slab formwork during concrete pouring operations and, thereafter, after the concrete has become set, facilitating lowering of the formwork away from the completed slab while at the same time stripping the formwork from the slab and then shifting the formwork laterally from beneath the slab for reuse elsewhere in the building undergoing erection. The invention is particularly concerned with a column-mounted shoring bracket of the screw jack type wherein the load-bearing member of the bracket embodies a leveling screw which supports the formwork during concrete-pouring and hardening operations and which, thereafter, is operated to pull the formwork downwardly and thus strip the same from the slab, after which tractional roller means forming a part of the shoring bracket allows the formwork to be shifted laterally for removal purposes.

Shoring brackets which operate upon the screw jack principle have been in use for quite some time, and so have brackets which, after lowering of the formwork, have facilities for tractionally rolling the formwork laterally out from beneath the concrete slab. Heretofore, all such existing or conventional shoring brackets of the general character under consideration are predicted upon the use of a screw jack which supports the load in compression, thus requiring the use of a relatively massive jack screw to withstand the load. Due to the relatively great length of the jack screw, the latter is subject to bending stresses, particularly at such time as it is fully extended for slab-supporting purposes during and after concrete-pouring operations. Construction operations which may be carried out above slab level after the concrete of the slab has hardened may effect load-shifting phenomena of sufficient magnitude as to initiate jack screw bending and once such bending of the jack screw has begun, the screw is greatly weakened and further bending will take place to completion and possible fracture.

The present invention is designed to overcome the above-noted limitation of compressional failure of the jack screws which are associated with currently known shoring brackets and, toward this end, the invention contemplates the provision of a novel composite shoring bracket wherein the vertically extending jack screw which supports above it the load-bearing traction roller or rollers functions in tension to support the load so that even when the effective length of the jack screw is at its maximum, i.e., when the associated formwork is in its uppermost slab-supporting position, the tension in the jack screw has a tendency to maintain the jack screw linearly straight rather than in a bent position. By such an arrangement, a considerably lighter jack screw than has heretofore been used in connection with shoring brackets of the type under consideration may be employed.

The provision of a shoring bracket of the jack screw type wherein, as aforesaid, the jack screw functions in tension to support and lower the load (associated formwork) constitutes the principal object of the present invention. Briefly, in carrying out this object, the invention contemplates the provision of a novel shoring bracket wherein the load-bearing traction roller means, instead of being mounted directly on the upper end of

the jack screw, is mounted on the upper end of a slide member which is vertically slidable on a fixed part of the bracket. The jack screw is effective between the lower end of the bracket and such fixed part of the bracket and thus the load, which is carried by the bracket, is transmitted through the slide member to the lower region of the jack screw, thereby placing the latter under tension during the time the formwork rests on the roller means on the slide member.

10 A further limitation that is attendant upon the construction and use of conventional column-mounted shoring brackets resides in the fact that such brackets are invariably fixedly mounted in toto on their respective building columns, thus requiring the use of a large number of such brackets during the erection of any given multi-story building. Since each bracket is of a composite nature and involves a large number of parts, both moving and stationary, duplication of these brackets throughout the building framework entails a large bracket inventory. Where the individual brackets are removable in their entirety from the columns for reuse in the same building installation, the labor that is involved in transferring them from one column to another on a different story level appreciably increases erection costs. The present shoring bracket obviates this latter limitation in that it is of two-part construction, one part being in the form of a fixed bracket support part which is of an inexpensive nature and is temporarily left in position on its associated column, and the other part being a removable part which includes the jack screw and its associated aforementioned slide member. By such an arrangement, the removable bracket part which is by far the most costly, may be transferred from column to column, the transfer being made with a minimum of effort and the anchoring of the removable part to the fixed part being accomplished by the simple expedient of placing a fast pin in position.

40 Additional objects and advantages of the invention, not at this time set forth, will become readily apparent as the following description ensues.

The invention consists in the several novel features which are hereinafter set forth and are more particularly defined by the claims at the conclusion hereof.

45 In the accompanying two sheets of drawings forming a part of this specification or disclosure, one illustrative embodiment of the invention is shown.

In these drawings:

50 FIG. 1 is a fragmentary perspective view of a concrete floor slab form installation, such view showing one of the improved column-mounted shoring brackets of the present invention operatively installed therein with the illustrated bracket being shown in its load-supporting position;

55 FIG. 2 is an enlarged perspective view of the shoring bracket of FIG. 1;

FIG. 3 is a vertical transverse sectional view of the bracket; and

60 FIG. 4 is an exploded perspective view of the improved column-mounted shoring bracket.

Referring now to the drawings in detail and in particular to FIG. 1, a shoring bracket embodying the principles of the present invention is designated in its entirety by the reference numeral 10 and is shown as being operatively installed upon a precast vertical concrete column 12 which is associated with and forms a part of a building undergoing erection. The function of the

bracket 10 is, in combination with identical brackets which are applied to other columns of the building, to support a formwork, such as that designated by the reference numeral 14, for a concrete slab during the time that the concrete of the slab is poured and thereafter while the concrete hardens after which manipulation of the bracket serves to lower the formwork bodily away from the slab until sufficient clearance is established as to permit lateral removal of the formwork from beneath the slab.

Formwork such as the formwork 14 herein disclosed will vary widely in different building installations. The particular formwork selected for illustration herein is only fragmentarily disclosed and it includes a longitudinal beam or stringer 16, a transverse beam member 18, and a plywood or other deck 20 on which the wet slab-forming concrete is poured for ultimate production of the floor slab (not shown). The shoring bracket 10 serves to support the associated beam 16 during concrete-pouring operations and, as will be described presently, after the concrete has become set, the bracket is capable of manipulation for the purpose of lowering the stringer 16, and consequently, the entire formwork 14. After the lowering operation, certain frictional roller means which is associated with the bracket 10 affords a substantially frictionless support for the lowered pallet-type formwork so that it may be slid endwise for use elsewhere.

Referring now to FIGS. 2, 3 and 4 of the drawings, the improved shoring bracket 10 involves in its general organization two main component parts, namely, a fixed column-attached shelf part 22 and a removable composite articulated jack part 24, the latter being comprised of two component parts as will be described more in detail presently. The shelf part 22 is of unitary construction and consists of three plates suitably welded together.

The fixed shelf part 22 is, in the main, comprised of flat plate stock and includes a rectangular backing plate 30, and a pair of vertically extending, forwardly projecting triangular shelf plates 32. A pair of vertically spaced bolt holes 34 (see FIG. 4) are formed in the backing plate 30 and are adapted for reception therethrough of the shank portions of respective bolts (not shown) by means of which the fixed shelf part 22 as a whole may be fixedly secured in position on the associated concrete column 12. Small pin-receiving holes 36 are formed in the upper portions of the shelf plates 32 and these are adapted for the reception of respective fast pins 38 by means of which the jack part 24 may be removably secured to the shelf part 22.

The jack part 24 of the shoring bracket 10 is comprised of three principal components, namely, a base frame 40, a vertically shiftable load-supporting carriage 42, and a vertical jack screw 44 by means of which the carriage 42 is caused to travel or move vertically with respect to the base frame 40. In FIGS. 2 and 3 of the drawings, the base frame 40 and the carriage 42 are shown in their effective assembled relationship, while in FIG. 4, said base frame and carriage 40 and 42 are separately illustrated in detached form.

The base frame 40 of the jack part 24 of the shoring bracket 10 consists of three spaced apart, horizontally extending parallel frame plates consisting of a pair of outside plates 50 and a relatively wide medial or central plate 52 (see FIG. 4). The three plates are maintained in their spaced relationship by means of front and rear,

horizontally extending angle pieces 54 and 56. An angle bracket 58 is welded to the forward end of one frame plate 50 and an angle bracket is welded to the rear end of the other plate 50. These two angle brackets are disposed diagonally opposite one another and have depending parts which are provided with holes 60. The latter are designed for register with the aforementioned holes 36 in the shelf plates 32 of the shelf part 22 of the shoring bracket 10 when the base frame 40 is applied to said shelf part. A hole 62 (see FIGS. 3 and 4) is formed centrally in the medial or central plate 52 of the base frame 40 for slidable reception of the upper end of the aforesaid jack screw 44. The latter is assembled upon the base frame 40 by first projecting the upper end of the same upwardly through the hole 62 after which a nut 64 is welded on such upper end while a loose collar 66 is then positioned on the jack screw 44 directly beneath the plate 52. Thereafter, a set collar 68 is mounted on the jack screw immediately beneath the loose collar 66. The nut 64, together with the collars 66 and 68, establishes a swivel connection for the upper end of the jack shaft 44.

The vertically shiftable carriage 42 of the bracket jack part 24 is of cage-like design and includes a pair of vertically extending channel pieces 70 which are disposed in back-to-back spaced apart relationship and are fixedly connected together at their lower ends by a transverse bottom plate 72. The plate 72 is preferably welded in place and has formed therein a central opening 74. A nut 76 is welded in position to the underneath side of the plate 72 so that its threaded bore is in register with the opening 74. The nut 76 threadedly receives the lower end portion of the jack screw 44 as clearly shown in FIGS. 2 and 3 of the drawings. The upper ends of the two channel pieces 70 are fixedly connected together by means of a pair of transverse plates and these consist of a front plate 78 and a rear plate 80 (see FIG. 4).

Means are provided at the upper end of the carriage 42 for tractively supporting the beam or stringer 16 of the pallet-type formwork 14 during the time that the concrete is being poured on the deck plate 20, as well as during lowering of the formwork 14, and also during the time that the formwork is being rolled out from beneath the previously completed slab. Accordingly, a horizontally disposed, transversely extending roller-supporting shaft 82 has its end regions rotatably journaled in aligned circular holes in the front and rear plates 78 and 80 and carries a load-supporting roller 84, the axial extent of which is slightly less than the distance between the plates 78 and 80, the roller substantially spanning such distance. The shaft 82 also carries an outside roller 86 of frustoconical design, the small base of the roller being disposed inwardly and facing the front plate 78. The roller 86 is of larger over-all diameter than the roller 84 and constitutes an edge guide roller for the purpose of preventing rolling of the beam or stringer 16 sidewise from the roller 84.

Various ways of assembling the base frame 40 and the carriage 42 of the bracket jack part 24 may be resorted to, one such way being to assemble the carriage 42, leaving the bottom plate 72 the last to be mounted and secured in place as indicated by the dotted line position of such plate in FIG. 4. Prior to welding the bottom plate 72 in position, the lower end portions of the two channel pieces 70 are inserted endwise through the voids 90 (see FIG. 4) which exist between the central

plate 52 and the two side plates 50 of the base frame, after which the plate 72 may be welded in position, thus causing the carriage 42 to be captured by the base frame 40. Thereafter, the jack shaft 44 may be threaded upwardly through the nut 76 so that it projects through the opening 74, after which the upper end of the jack shaft, the nut 64, and collars 66 and 68 may be assembled in position in the manner previously indicated.

In the installation and operation of the herein described shoring bracket 10 in association with a multi-story or high-rise concrete building, the requisite number of brackets 10 will be mounted on the concrete columns of the building in order to accommodate the particular pallet-type formwork 14 being utilized in the formation of a concrete floor slab above the formwork 20. The various jack screws, the lower ends of which are provided with square end portions 92 for facilitating manipulation by a wrench or other suitable turning tool, will be adjusted to bring the associated rollers 84, 86 approximately to the same general horizontal plane at the desired deck height, and thereafter, the formwork 14 will be lowered onto or otherwise caused to rest upon the rollers 84. Initial application of each bracket 10 to a column 12 is made by bolting the shelf part 22 to the column and, thereafter, applying the jack part 24 to the thus fixed shelf part 22. Such application is made by setting the jack part on the upper horizontal edges of the triangular plates 32 and causing the holes 60 in the angle brackets 58 to register with the holes 36 in the triangular shelf plates. Thereafter, the fast pins 38 are passed through the registering holes in order to lock the two bracket parts 22 and 24 together.

In the operation of the shoring bracket 10, it will be noted from an inspection of FIG. 1 that the beam or stringer 16 rests squarely on the roller 84 while the roller 86 serves as an edge guide for preventing inadvertent derailing of the beam or stringer. At such time as the pallet-type formwork 14 is thus positioned on the various brackets, a leveling operation may be instituted so as to bring the plywood deck 20 to the desired level. Also at this time, slight longitudinal adjustment of the formwork may be resorted to if necessary.

With the formwork 14 thus resting on the rollers 84, pouring of the concrete or other forming operations are conducted and when it is time to remove the formwork the jack screws 44 of the brackets 10 are manipulated by application of a suitable wrench or the like to the squared ends 92 thereof so as to lower the load-supporting carriages 42, thereby also lowering bodily the formwork as a whole away from the completed superjacent floor slab. When it is ascertained that the formwork is at a proper level for removal thereof from the installation, it can readily be rolled longitudinally on the roller 84 out from beneath the formed slab.

In most instances, upon release of upward pressure on the formwork 14, there is a tendency for the plywood deck 20 to remain adhered to the hardened concrete thereabove. In such a situation, it is customary forcibly to pull the formwork, or pry it, from its adhered position. In the present instance, loosening of the bond between the deck 20 and the concrete may be effected by passing a chain or metal strapping around the beam 16 and causing it to be hooked to or engaged with any appropriate part of the movable carriage 24 of each or any one of the shoring brackets 10 so that lowering of the carriage under the influence of the jack

screw 44 will exert a powerful downward pull upon the formwork 14, the combined pull of all of the carriages 24 associated with the various brackets 10 being adequate for deck dislodgment.

It is to be noted that in connection with the operation of the herein described shoring bracket 10, the load of the formwork is at all times applied to the jack screw 44 in tension, such tension existing in that portion of the jack screw which extends between the medial plate 52 and the base frame 40 and the bottom plate 72 of the carriage. While the relatively sturdy carriage 24 remains in compression, the jack screw 44 remains in tension. By such an arrangement, it is not necessary to employ the relatively massive jack screws which ordinarily are associated with shoring brackets of the type where the formwork loads place a direct compressional thrust on the jack screws.

The invention is not to be limited to the exact arrangement of parts shown in the accompanying drawings or described in this specification as various changes in the details of construction may be resorted to without departing from the spirit or scope of the invention. Therefore, only insofar as the invention is particularly pointed out in the accompanying claims is the same to be limited.

Having thus described the invention what we claim as new and desire to secure by letters patent is:

1. A shoring bracket adapted to support a horizontal stringer forming a part of a concrete-receiving, pallet-type formwork used in the erection of a multi-story building, said bracket comprising a horizontal base frame having means whereby it may be fixedly secured to a vertical column of the building, a vertically elongated carriage mounted with respect to the base frame so that it is slidable vertically between a raised and a lowered position, a loadbearing roller on the upper end of said carriage, a vertical jack screw having its upper end swivelly connected to the base plate and depending therefrom, and means establishing a threaded connection between said jack screw and the lower region of the carriage, whereby rotation of the jack screw in opposite directions will effect raising and lowering of the carriage and formwork with the intervening region of the jack screw between such threaded connection and base frame supporting the carriage and formwork under tension.

2. A shoring bracket as set forth in claim 1 and wherein said shoring bracket is of a composite two-part separable nature and includes a shelf part designed for permanent and fixed attachment to the vertical column of the building and a jack part removably mounted on the shelf part, said jack part embodying said base frame.

3. A shoring bracket as set forth in claim 2 and wherein said shelf part includes a backing plate designed for face-to-face application to the building column, and a shelf member projecting forwardly from said backing plate, base frame is removably supported on said shelf member, and there is provided releasable locking means effective between the base frame and shelf member for maintaining the former in position on the latter against dislodgment.

4. A shoring bracket as set forth in claim 3 and wherein said shelf member comprises a pair of vertically disposed spaced apart shelf plates disposed in edge-to-face relationship with respect to said backing plate and presenting horizontal upper edges upon

which the side edges of said base frame rest, and said releasable locking means embodies a pair of fast pins which project through pairs of aligned openings in the shelf plates and depending fastening brackets which are mounted on the base.

5. A shoring bracket as set forth in claim 3 and wherein said base frame is provided with laterally spaced voids, the carriage is of cage-like construction and embodies a pair of side members which are slidable through said voids.

6. A shoring bracket as set forth in claim 5 and wherein said side members are connected together at their lower ends by a bottom plate which carries a nut through which the jack screw extends.

5 7. A shoring bracket as set forth in claim 6 and wherein said jack screw projects upwardly through said carriage centrally thereof and between said side members.
